UNITED STATES PATENT OFFICE.

CARL SCHOU, OF HOLTE, DENMARK.

TRANSMITTER FOR WIRELESS TELEGRAPHY.

1,158,309.

Specification of Letters Patent. Patented Oct. 26, 1915.

Application filed January 12, 1914. Serial No. 811,726.

To all whom it may concern:

Be it known that I, CARL SCHOU, a subject of the King of Denmark, residing at Holte, Denmark, have invented certain new and useful Improvements in Transmitters for Wireless Telegraphy, of which the following is a full, clear, and exact description.

Apparatus for very rapidly establishing 10 interrupting or reversing weak telegraphic currents in accordance with the telegraph signals are known in connection with wire telegraphy and the present invention has reference to the use of such apparatus for 15 interrupting and establishing weak currents with a view to producing the necessary variations in the far stronger currents used for radio telegraphy. For this purpose relays are used in which a spring actuated armature is kept in direct contact with the cores 20 of electromagnets and retained against the action of a spring by residual magnetism, which magnetism is neutralized by a weak current having a direction opposite to that 25 of the stronger current which has caused the attraction of the armature and produced the residual magnetism. The closing of the secondary circuit is effected by the armature being pulled away from the magnets under 30 the influence of the spring, and as the spring acting upon the armature can be made rather heavy, a fair pressure is secured between the contact making parts in question.

Relays of this kind are especially suited 35 for the purpose set forth because at a certain speed of telegraphy current impulses of a certain short duration are produced and by distributing the work on a plurality of relays sufficient time can be provided for enabling the movable parts of each single relay 40 to perform their movements, which movements need not be accomplished by the time when the current impulse releasing the relay has ceased. It is hereby possible to provide 45 a transmitter capable of working at a very great speed.

In the annexed drawing Figures 1-4 show 50 by way of example different diagrammatic arrangements in accordance with the present invention. Fig. 5 is a view showing the connection between the Wheatstone transmitter and the rest of the apparatus.

In Fig. 1 A designates the contact device

of an ordinary Wheatstone transmitter. Only one of the contacts viz. *a*, is here used. The relays *b*¹, *b*², *b*³, *b*⁴ four of which are used in the example shown, are of such a construction that in the contact position shown the armatures rest against the iron cores in the magnets, so that the magnetic circuit is totally closed, and the armature is retained by residual magnetism also after the magnetizing current is cut off. The contacts *c*, *d*, *e* and *f* are opened when the armatures are attracted, but as soon as a weak current impulse is sent through the coils of a relay in opposite direction to that of the current which has effected the magnetizing, the armature is drawn off by one of the springs *g* and the contact in question is closed.

Thirteen commutator disks or slip rings *h*, *i*, *j*, *k*, *m*, *n*, *o*, *p*, *q*, *r*, *s*, *t* and *u* are arranged on a shaft geared to the crank shaft of the Wheatstone transmitter in such a manner that it describes half the number of revolutions of the latter. Springs or brushes are applied against these disks or slip rings as shown, diagrammatically in the accompanying drawing. By means of wires led along the shaft and participating in the rotation, the conducting segments 1, 2, 3 and 4 on the disk *h* are respectively connected with the four slip rings *i*, *k*, *n* and *p* in the manner indicated in dotted lines, and these slip rings are in turn respectively connected with segments on the disks *j*, *m*, *o* and *q* as shown. The commutator disk *h* serves for distributing the work over the four relays.

By means of the gearing between the shaft carrying the commutator and the Wheatstone transmitter provision is made that the contact *a* closes for a period corresponding to the length of a dot, when the contact spring of the commutator disk *h* has just come in contact with a conducting segment and the current impulse has ceased before the spring has left the same. The commutator disks *j*, *m*, *o* and *q* serve for effecting the attraction of the armatures of the relays after the same have been released. The commutator disks *r*, *s*, *t* and *u* are constructed so as to stand the effect of the establishing and interrupting of the strong telegraphic currents, and in the example shown the contact springs of the commutator disks are arranged in series

each with one of the contacts *c*, *d*, *e* and *f* of the relays. The battery *v* serves for releasing the relays, and the battery *w* for effecting again the attraction of the armatures.

Referring to Fig. 5 of the drawing, the connection between the Wheatstone transmitter and the rest of the apparatus will be clearly understood.

- 10 9 represents the crank shaft, 15 the rocking beam, and 10 is a gear on the crank shaft meshing with a gear 11 on the shaft 16 carrying the various distributing disks, one of which *h* only is shown in this figure.
- 15 If it be imagined that all the commutator disks are turned in the direction of the hands of a watch, and it is desired to transmit a dot, this is effected in the following manner: As soon as the spring *x* has come
- 20 into contact with the segment *l* for instance the contact *a* is closed and the battery *v* sends a current through the electromagnet of the relay *b*, the slip ring *i*, the segment *l*, the spring *x* and the contact *a*, whereby
- 25 the armature is released and closes the contact, *c* owing to the action of the spring *g*. The contact at *a* must, as already stated, have ceased before the contact spring *x* has left the segment *l*. The contact at *c* requires
- 30 a certain short time for being closed owing to the inertia of the parts and does not need to be closed when the spring *x* leaves the segment *l* but only before the segment on the disk *r* established the connection be-
- 35 tween the corresponding slip springs. As soon as this occurs, the circuit influencing the radio telegraphic transmitting system is closed through the wire *y*, the contact springs, the contact *c* and the wire *z*. The
- 40 length of the period during which the circuit is closed depends upon the length of the segment on the disk *r*, and is about one fourth of the time required by the shaft for performing one revolution. When the
- 45 segment on the disk *r* has passed the contact springs and thereby interrupted the currents, the current effecting the attraction of the armature of the relay *b* is established so that the contact is interrupted at *c*.
- 50 The magnetizing current in question is established, the segment on the disk *j* passing its contact springs. The current then passes from the battery *w* through the commutator disk *j*, the slip ring *i*, the coil of
- 55 the magnet and back to the battery *w*.
- If the contact at *a* is permanently established it is seen that all the relays will get into activity consecutively, and an electric connection will permanently be established
- 60 between the wires *y* and *z*. If the paper slip sent through the Wheatstone transmitter is perforated in such a manner that three relays get into activity consecutively this will effect the transmitting of a dash in the
- 65 Morse system.

The arrangement of the parts shown in Fig. 2 only differs from that shown in Fig. 1 by the fact, that while in Fig. 1, the set of contact springs belonging to the commutator disks *r*, *s*, *t*, and *u* are placed in series 70 each with one of the contacts *c*, *d*, *e* and *f*, these groups being arranged in parallel on the lines *y* and *z* in Fig. 2 the contact springs belonging to the commutator disks *r*, *s*, *t* and *u* are arranged in series and each *per se* connected in parallel with the contacts *c*, *d*, *e* and *f*. In this arrangement the commutator disks *r*, *s*, *t* and *u* must be conducting over about three fourths of their circumferences, and the moments for closing or interrupting 80 of the contacts *c*, *d*, *e* and *f* must fall within the periods during which the contact springs are short circuited by the commutator disks *u*, *v*, *s* and *t*. In this manner sparking at the contacts *c*, *d*, *e*, and *f* is also avoided.

85 The arrangement shown in Fig. 3 corresponds in all essentials to that shown in Fig. 1. The only difference is that instead of the four commutator disks *r*, *s*, *t* and *u*, only two such disks are used, viz: the disks 5 and 6, 90 the former of which plays the part of the disks *r* and *t*, while the latter replaces the disks *s* and *u*. The commutator disks 5 and 6 are, as shown, geared to the shaft of the other commutator disks, so that the disks 5 and 6 make the double of the number of revolutions made by the disks in Fig. 1. This arrangement entails a reduction in 95 number of the large commutator disks, but at the same times gives rise to the drawback that the relays get a somewhat shorter time for performing their functions.

100 The arrangement shown in Fig. 4 is identical with that shown in Fig. 3, with the exception that instead of the two commutator disks 5 and 6 two condensers 7 and 8 are used, which are constructed in such a manner that one of their armatures is stationary, while the other one is sector-shaped and rotates, being mounted on the shaft geared to 110 that carrying the commutator disks. The contacts of the relays are opened and shut when the capacity of the condenser in question is practically equal to naught. Hereby 115 sparking at the contacts of the relays is also avoided. As in the above case the wires *y* and *z* are also here connected with one of the circuits of the transmitting system, and the alteration which the capacity of a condenser undergoes by the sector swinging past the 120 stationary armature will, if one of the corresponding contacts be closed, effect an alteration of the length of energy of the waves transmitted.

125 Having thus fully described my invention, I claim as new and desire to secure by Letters Patent:

In an apparatus for transmission of telegraphic signals a plurality of relays each having a spring actuated armature adapted 130

to be retained by residual magnetism and to be released by relatively weak currents, a source of electricity, a number of contact making elements adapted to connect the said 5 relays with the said source of electricity, a transmitter mechanically connected to the said contact making elements, and a distributing device mechanically connected to the said transmitter and adapted to distribute signal currents from the said transmitter to over the said relays.

In witness whereof, I have subscribed my signature, in the presence of two witnesses.

CARL SCHOU.
